GEORGE W. WEBER, OF ST. PAUL, MINNESOTA, ASSIGNOR TO AMERICAN CAN COMPANY,
OF NEW YORK, N. Y., A CORPORATION OF NEW JERSEY.

PANELED ASPARAGUS-CAN.

1,262,289.

Specification of Letters Patent.

Patented Apr. 9, 1918.

Application filed March 31, 1913. Serial No. 757,846.

To all whom it may concern:

Be it known that I, GEORGE W. WEBER, a citizen of the United States, residing in St. Paul, in the county of Ramsey and State of Minnesota, have invented a new and useful Improvement in Paneled Asparagus-Cans, of which the following is a specification.

This invention relates to improvements in cans adapted for shipping asparagus or other food-stuffs which of necessity must be so packed and held within the can or container, that the food-stuff cannot move around in the can and become mashed or broken from rough handling during shipment.

Hitherto, glass bottles or jars have sometimes been used for shipping asparagus, but it has been found that the light which passes through glass, not only bleaches the asparagus to an undesirable grayish yellow color, but also toughens the asparagus, and for these reasons and also for the further reason that glass containers are not adapted for rough handling, the use of glass has been practically abandoned in favor of tin containers.

Of the sheet metal containers, which have been used for packing asparagus, there are two types generally used, the same being the well known cap-hole type of can and the oblong round corner type of can. The cap-hole can, however, while possessing some advantages over other forms of containers, is undesirable for the reasons that it is not of the so-called "sanitary" type which is now being demanded more and more by the public; the asparagus stalks must be packed one at a time through the relatively small opening at the top; and furthermore, because of the difficulty in lacquering or coating the interiors of such cans which, when not coated, are attacked by the vegetable acids or gases which cause the formation of large quantities of salts of tin, these salts being sometimes formed in such large quantities that the Government will reject the pack on the ground that the quantity of salts exceeds the amount allowed by law. The oblong round corner cans are most generally used and preferred on account of the fact that the same are more easily filled and coated, but this type of can is objectionable for the reasons that the seam-forming flanges at the corners of the can break easily, thereby preventing the formation of perfect

hermetic seams and because of the difficulty encountered in forming a tight double seam along a straight side. In practice, it is found that when forming a double seam along a straight side of a can, the flange on the can body backs up during the seaming operation and does not unite with the flange of the can end as it should and does in the case of the ordinary "sanitary" round cans. Also in the rectangular or oblong cans, the strength of the seam uniting the body and ends is limited to the strength of the folded portions which sometimes permits of the seam being broken from internal pressure, whereas, in the case of the double seamed round can, the seam tightens up like a hoop on a barrel and on account of its circular shape, it is practically impossible to unfold the seam by pressure from the interior of the can.

The object of my invention is to provide a sheet metal can which is of the so-called "sanitary" type, having cylindrical end portions whereby the ends may be easily double seamed thereto, which is free from all of the objectionable features of the cap-hole and oblong round corner cans, above indicated, which when sealed under a vacuum, will have its paneled sides collapse so as to firmly hold the asparagus or other food-stuff in position and prevent the same from moving about within the can during shipment to thereby preserve the contents intact until delivered to the consumer, and in which the collapsed, paneled sides, being flexible, will accommodate any harmless gases which may be generated within the can after sealing to thereby prevent the formation of what are known as "swell heads".

The invention furthermore consists in the improvements in the parts and devices and in the novel arrangement of the parts and devices as herein shown, described or claimed.

In the drawing forming a part of this specification, Figure 1 is a perspective view of a sheet metal can embodying my improvements. Fig. 2 is a similar view of the can illustrated in Fig. 1, showing the same after the panels have collapsed, and Fig. 3 is a sectional view of the can shown in Fig. 2, taken substantially at the longitudinal center of the can.

In said drawing, the can is designated generally by the reference A, and, as shown,

comprises a body member B and a bottom C, the latter being united to the body by means of a double seam 10. The body B is normally substantially cylindrical throughout, and when supplied to the packer will be provided with the usual seam forming flange 11 at the top, and a plurality of beads, creases, ribs, indentations or other suitable panel outlining means 12 so arranged that the portion of the can body intermediate the ends, is divided into a plurality of panels 13, which as shown, have parallel sides and converging upper and lower ends, the number of such panels shown in the drawing being five, although a greater or less number may be used if desired. The said beads enable the tin of the container body to naturally bend where the beads are located, promote the desired collapse of the panels and constitute means which maintain the ends of the container of cylindrical contour. The shape of collapsible panel illustrated, with rounded or narrowed upper and lower ends, closely approximates the form of panel which naturally tends to form on the side of a cylindrical can when it is subjected to considerable exterior atmospheric pressure; and this form of panel will collapse more at the middle than will panels of substantially rectangular form without narrowed ends. The can is also provided with an interior protective coating 14 of lacquer or other suitable material to prevent the tin being attacked by the vegetable acids or gases.

Inasmuch as the can, when supplied to the packer, is substantially cylindrical from end to end and is provided with a large open top, the same may be easily filled by placing the entire bunch of asparagus or other substance at one time in the can, and as is usual, the contents of the can will then be "processed" or cooked by being passed through an exhaust box or cooker, and while the contents are still hot and the air in the space at the top of the can in a rarefied condition, the cover or closing end can be easily double seamed to the body. After the can has been sealed and the contents allowed to cool, a vacuum will be created within the can, which will cause the flexible paneled portions 13 of the can to collapse as shown at 13^a in Figs. 2 and 3, the collapsible areas being determined and defined by means of the beads or creases 12 which outline the panels and which also serve as strengthening means so that the portions of the can outside of the outlined paneled portions will be unaffected by the vacuum. This action causes a decrease in the cross sectional area of the

can at the central portion thereof, so that the asparagus or other food-stuffs will be firmly gripped by the middle panel portions and prevented from longitudinal movement in either direction or rotative movement 65 within the can, and at the same time the delicate tips of the asparagus stalks still occupy as large a space as when first placed in the can and therefore will not be crushed or injured.

As indicated in the foregoing, after the can is sealed, any harmless gases which may be generated within the can, will be accommodated by the outward yielding of the collapsed panel portions which are more 70 flexible than the can ends, the latter in actual practice being formed with a number of ribs or grooves which increase the strength of the ends, thereby preventing the formation of "swell heads," that is, cans 75 having their ends bulged outwardly and which cannot be sold to the trade even though the contents of the can are in perfect edible condition, these "swell heads" sometimes causing a large loss to the packer. 80

I claim:

1. A sheet metal can for hermetically inclosing and gripping food products such as asparagus, the sides of said can being cylindrical from end to end and having cylindrical end portions of substantially the same diameter, and the can having its sides between said end portions outlined with panels and normally, before the can is filled, circular in cross section, which circular middle 95 portion becomes of less cross sectional area than is either of the cylindrical end portions by the regular collapsing of the said panels, so as to grip and hold the food product by the said panels at the middle part of the 100 can and hold the same from movement within the can, the said panels having curved narrowed ends which are outlined by means bent from the metal of the can body and which promote, and define the limits of, the 105 said collapsing and maintain the can of regular form and the ends of the same of cylindrical contour.

2. A sheet metal can for hermetically inclosing and gripping food products, the body of said can being cylindrical, and being formed with means for defining collapsible panels thereon, whereby a partial vacuum produced within the can will cause the regular collapse of the defined panels 115 and the holding of the food product.

GEORGE W. WEBER.
